SLUG CASTING MOLD

Einar G. Klingberg, Long Island City, and David L. Anderson, Brooklyn, N. Y., assignors to Intertype Corporation, Brooklyn, N. Y., a corporation of New York

Application September 17, 1935, Serial No. 40,968

15 Claims. (Cl. 199—57)

The present invention relates to improvements in liners for typographical molds used in casting type bars or slugs, and more especially for molds of the kind employed in typographical machines of the general class disclosed in U. S. Letters Patent No. 436,532, granted September 16, 1890 for casting a type bar or slug against a line of matrices presented to the face of the mold with the characters on one edge thereof aligned with the casting slot in the mold, one of the liners, in molds of this kind, being adjustable to determine the length of the mold slot in accordance with the length of the matrix line.

One of the primary objects of the invention is to provide means for positively locating and rigidly retaining the mold liner in the mold so that the front and back edges of the liner will be held with certainty in exact alignment with the corresponding faces of the mold, irrespective of the length of the liner or its position longitudinally of the mold slot in the event the liner is of a short length and divides the mold slot into a plurality of casting compartments. Accordingly, the liner, according to the present invention, is provided with a longitudinally extending rib or other similar projection, preferably on the underside thereof adjacent to the casting surface of the mold body, and the mold body is provided with a corresponding longitudinal groove to receive the rib or projection on the liner. The rib on the liner and the groove in the mold may be of such shallow form as to not interfere with ejection of the cast slug when pushed forwardly as usual out of the mold, or the groove in the mold may be relatively deep and wide to accommodate a rib of correspondingly increased size on the liner, the rib in that event extending sufficiently beyond the liner to completely fill up the groove in the mold and present a smooth or flush casting surface.

To these and other ends, the invention consists in certain improvements and combinations and arrangements of parts all as will be hereinafter more fully described, the features of novelty being pointed out particularly in the claims at the end of this specification.

In the accompanying drawing:

Figure 1 is a front elevation of a mold and a part of the mold disk or support commonly employed on commercial slug casting machines, the mold being provided with liners according to the present invention;

Figure 2 is a top plan view of the body or base of the mold, showing the shallow groove to receive the shallow rib on the liner, this view represent-

ing a section taken on the line 2—2 of Fig. 1 and looking in the direction of the arrows;

Figure 3 is a view similar to Fig. 2 but illustrating a deep and wide groove in the mold body to receive a correspondingly deep and wide rib on the liner according to the present invention;

Figure 4 is a transverse vertical section taken on the line 4—4 in Fig. 1;

Figure 5 is a transverse vertical section taken on the line 5—5 in Fig. 1;

Figure 6 is a transverse vertical section taken on the line 6—6 in Fig. 3;

Figure 7 is a transverse vertical section taken on the line 7—7 in Fig. 3; and

Figure 8 is a detail perspective view of one of the shallow rib liners according to the present invention.

Similar parts are designated by the same reference characters in the different figures.

The mold as shown in Figure 1 comprises as usual an upper part or cap 1, a lower part or body 2 to which the cap is secured as by bolts 3, the mold body being secured by screws 4 to the face of the usual mold disk or support 5. The mold disk is rotated, as usual and well known in machines of this class, to present the mold to the matrix line and casting mechanism for the injection of molten metal into the mold slot and against the characters in the matrix line, and to carry the mold containing the cast slug therein to a position in front of ejecting mechanism including a blade which is movable forwardly from the rear side of the mold through the mold slot to eject the slug edgewise and in a direction transversely of its length from the mold.

The slot 6 in which the slug is cast is disposed between the cap and body of the mold, it being defined by the bottom or casting face of the cap and the opposed upper or casting face of the mold body, and the ends of the casting slot are defined by the right hand and left hand liners 7 and 8 respectively, which may be of different thicknesses according to the separation desired between the cap and body of the mold in order to vary as desired the thickness or point size of the slugs to be cast in the mold. The liners 7 and 8 are provided with bores 9 and 10 respectively to receive short studs 9^a and 10^a respectively which project downwardly from the bottom face of the mold cap, and short studs 9^b and 10^b respectively which project upwardly from the upper face of the mold body, these studs serving to accurately locate the liners and the mold cap longitudinally with respect to the mold body.

According to one embodiment of the invention shown in Figures 1, 2, 4, 5 and 8, the upper or casting face of the mold body 2 is provided with a shallow longitudinal groove 11 which preferably extends continuously throughout the length of the upper face of the mold body, and the liners 7 and 8, and also extensions thereof as herein-after described, are each formed with a rib of the same width and depth as the groove 11, the liner 7 being shown provided with such a rib 7^a and the liner 8 being shown provided with such a rib 8^a. Consequently, when the liners 7 and 8 are placed on the mold body they will be properly located longitudinally of the mold by engagement of the bores 9 and 10 with the studs 9^a and 10^a and 9^b and 10^b respectively, and the liners will be firmly held against displacement laterally of the mold by engagement of the ribs 7^a and 8^a thereon in the groove 11 in the mold body.

The advantages of the rib and groove construction for the liners and mold as just described are of particular importance under certain conditions in the operation of typographical machines of the class referred to. For example, if the system employed in respect to mold liners is to employ a series of left hand liners of different lengths for varying the length of the mold slot for casting slugs of different lengths, it will be seen that to obtain a relatively short mold slot, the left hand liner in Fig. 2 may be of a length to extend from the extreme left hand end of the mold body to a point indicated by the dotted line A, and without the rib 8^a on the liner and the cooperative groove 11 in the mold body, a liner of such length would be anchored or held against lateral displacement in the mold only by the studs 10^a and 10^b and would be held against lateral swinging displacement about the studs 10^a and 10^b only by the frictional engagement between the liner and the opposed casting faces of the mold cap and body. Without the rib on the liner and cooperating groove in the mold body, the liner might be inserted carelessly without bringing its edges flush with the front and rear faces of the mold before securing the bolts 3, which would be objectionable and is avoided by the present invention. Also, when employing an adjustable liner, such as the liner 13 having a rib 13^a on its underside to fit into the longitudinal groove 11 in the upper or casting face of the mold body 2, to vary the length of the mold slot or divide the slot into a plurality of compartments, as indicated by the dotted lines in Fig. 2, the rib 13^a on such a liner and the cooperative groove 11 in the mold body serve to positively locate and firmly retain such liner against lateral displacement. When using the adjustable liner 13, the left hand liner 8 is made relatively short, as shown in Fig. 2, and the liner 13 is placed adjacent to the liner 8 so that the length of the mold slot between the liner faces 14 and 17 at opposite ends of the mold will be such as to give the maximum length slug for which the mold or the machine is intended to cast. Thus, if the machine is limited to the casting of thirty em slugs, then the length of the mold slot between the liner faces 14 and 17 will be thirty ems when the liner 13 is placed against the end of the liner 8. If it is desired to adjust the mold slot to a length less than thirty ems, the short liner 13 is moved along the mold slot between the mold cap and body to the desired point as shown for example by the dotted lines in Fig. 2. Under this condition, the slug would be cast between the faces 14 and 17 of the liners 7 and 13 respectively,

and during casting of the first slug, metal would also be injected into the vacant portion of the mold slot between the face of the liner 8 and the face 18 of the liner 13. The dummy slug thus cast in the vacant portion of the mold slot during the first casting operation would remain in the mold until such time as it may become necessary to change the length of the active portion of the mold slot between the left hand and right hand liners. The liner 13, when once placed at the desired point in the length of the mold slot will be firmly retained against lateral displacement by engagement of its rib 13^a in the groove 11 in the casting face of the mold body, and such engagement of said rib and groove 15 will locate this liner laterally with its front and rear edges flush with the front and rear faces of the mold. Longitudinal displacement of the liner 13 is prevented by clamping thereof between the mold cap and body.

According to another embodiment of the invention, shown in Figs. 3, 6 and 7, a longitudinally extending groove 19 is provided in the upper or casting face of the mold body 2 and extends across said face, this groove being wider and deeper than the groove 11 previously described. The left hand liner 20 carries a rib or longitudinal projection 21 which is fastened to its underside, as by rivets 22, the rib or member 21 corresponding to the rib on each of the liners 7, 8, and 13 but extending beyond the liner 20. Similarly, the right hand liner 23 carries a rib or member 24 which corresponds to the rib or member 21, to cooperate with the groove 19 in the casting face of the mold body, the inner end 25 of the rib or member 24 being offset outwardly from the inner face 26 of the liner 23.

When the left hand liner 20, with an inner face 27 is used to give the maximum length to the mold cavity, the rib or member 21 secured to the underside of the liner 20 will be of sufficient length to reach beyond the inner end 26 of the right hand liner 23, and when placed in the mold it will fill up the groove 19 to present a smooth or unbroken casting face on the mold body, the rib or member 21 being of a thickness equal to the depth of the groove 19, and the rib or member 21 will overlap the right hand liner 23 and substantially meet the end 25 of the rib or member 24 on the underside of the liner 23, thus serving to produce a metal tight joint between the end 26 of the liner 23 and the mold body. On the other hand, if it is desired to use a left hand liner similar to the liner 20 but of such length that its inner face, represented by the dotted line 28 in Fig. 3 produces a relatively short casting slot in the space between the liner faces 26 and 28, the rib or member 21 will be preferably of the same length as previously described for the liner 20 but secured to the longer left hand liner by an additional rivet 29 adjacent to the inner end 28 of such liner.

The rib or member 21 secured to the left hand liner, especially when secured thereto near its inner end, will provide means for alining the front and rear edges of the liner with the front and rear faces of the mold and prevent any lateral displacement or swinging motion of the liner about the studs on the mold cap and body which engage in the holes 10, which would be likely to occur if the inner end of the liner were not securely held in place.

In the embodiment of the invention shown in Figs. 1, 2, 4, 5 and 8 employing the shallow groove 75

11 in the casting face of the mold body, metal will flow into this groove over the extent thereof exposed between the inner faces of the right hand and left hand liners when a slug is cast. However, this groove 11 is of such small dimensions that, although it serves adequately for locating and firmly anchoring the liners against lateral displacement, the bead cast on the slug will be so narrow that it will not interfere with the pushing of the slug edgewise forwardly out of the casting slot in the usual manner. It has been found in practice that by forming this groove 11 with its side walls 39 and 31 perpendicular to the casting face of the mold body, the bead cast therein and formed on the slug will be instantly sheared from the underside of the slug when the latter is struck by the usual ejector blade to push the slug forwardly out of the mold, the bead cast in the groove 11 remaining therein. After the first slug is cast, subsequent slugs will not have such a bead formed on them, since the groove 11 will be filled by the bead sheared off the first slug. It is only necessary to lift the sheared off bead out of the groove 11 when different liners are placed in the mold.

In the embodiment of the invention shown in Figs. 3, 6 and 7, a smooth or unbroken casting face is maintained on the mold body, the rib or member 21 being of such a thickness that its upper face is flush with the casting face of the mold body.

In each embodiment shown and described, the cooperative groove and rib serve to accurately locate the liner in the mold with its front and back edges flush or in face-wise alinement with the front and back faces of the mold so that these faces will form the required metal-tight lock up with the matrix line and usual metal pot mouth-piece, and to securely hold the liner against lateral displacement from the mold under the force applied by the usual ejector blade 32 in a direction transversely of the length of the mold, as indicated in Fig. 4, incident to the ejection of the slugs from the mold, such holding of the liner or liners being rendered especially effective by engagement of the rib or retaining member on the liner with the mold adjacent to the inner or casting end of the liner.

Furthermore, the present invention provides relatively simple and effective means for locating a liner at different points in the length of the mold slot and securely retaining it against displacement in a direction transversely of the mold.

We claim as our invention:—

1. In or for a slug casting machine having a longitudinally slotted mold for casting slugs therein and means for ejecting the slugs from the mold in a direction transversely thereof, a mold comprising spaced members forming a slug casting slot between them, a liner between said members for closing an end of said casting slot, and means connecting the portion of said liner adjacent to its inner casting end directly to one of said mold members irrespective of the position of the inner end of the liner longitudinally of the mold to secure the inner end of the liner against displacement transversely of the mold.

2. In or for a slug casting machine, a mold comprising opposed members spaced to form a slug casting cavity between them and alined at the respective opposite faces of the mold, a liner between said members for closing an end of the casting cavity, means for clamping the liner between said members, and means extending lon-

gitudinally over the full extent of said cavity for connecting the inner casting end of the liner to one of said members to aline the edges of the liner with the respective faces of the mold.

3. In or for a slug casting machine, a mold having a slot-like slug casting cavity therein and having a groove extending longitudinally throughout the length of a wall of said cavity, and a liner for closing an end of said cavity and having a portion thereon engageable in said groove.

4. In or for a slug casting machine, a mold having a slug casting cavity therein and having a groove extending throughout a casting face of said cavity, and a liner closing an end of said cavity and having a rib secured thereto at one side and engaged in said groove.

5. A slug casting mold having an elongated casting cavity therein and having a groove extending longitudinally in a wall of said cavity, and a liner the inner end of which closes an end of said cavity and having a portion projecting therefrom flush with its inner end and engaged in said groove.

6. A slug casting mold having an elongated slug casting cavity therein and having a groove extending longitudinally in a wall of said cavity, and a liner having an end adapted to occupy different positions longitudinally of the mold to close an end of said cavity and having a portion projecting therefrom adjacent to its said end and engageable in said groove to close the latter at the point along the cavity closed by the end of the liner.

7. A slug casting mold having an elongated slug casting cavity therein and having a groove extending longitudinally in a wall of said cavity, and a liner adjustable longitudinally of said cavity to close an end and determine the length thereof and having a portion thereon engageable in said groove to close the latter at the adjusted position of said liner.

8. A slug casting mold comprising opposed members spaced to form a casting cavity between them, one of said members having a groove there-in extending longitudinally over the extent of its casting face, a liner between said members and closing an end of said cavity and having a portion thereon engageable in said groove, and means for clamping the liner between said members.

9. A slug casting mold having an elongated slug casting cavity therein and having a shallow narrow groove extending longitudinally in a casting wall of said cavity adapted to be filled with metal injected into the casting cavity, and a liner closing an end of said cavity and having a portion projecting therefrom and engageable in said groove.

10. A slug casting mold comprising opposed members forming faces of a casting cavity, one of said faces having a groove extending longitudinally therein, end liners between said members, an intermediate liner between said end liners and adjustable longitudinally of the mold, said end and intermediate liners having longitudinal ribs projecting therefrom and engageable in said groove, and means for clamping said liners between said members.

11. A slug casting mold having a slug casting cavity therein a casting face of which is provided with a longitudinal groove, and a liner closing an end of said cavity and having a portion connected thereto and extending therefrom

60

55

into the portion of said groove within the casting cavity and filling said portion of the groove.

12. A slug casting mold having a slug casting cavity therein a casting face of which is provided with a longitudinal groove, and a liner closing an end of said cavity and having a portion extended therefrom into the portion of said groove which lies within the casting cavity, said extended portion being of a cross section corresponding with that of the groove to fill the same and to present a surface flush with the grooved casting face of said cavity.

13. A slug casting mold having a slug casting cavity therein a casting face of which is provided with a longitudinal groove, and a liner closing an end of said cavity and having a rib secured thereto at its inner cavity closing end and extending across said cavity in said groove.

14. A slug casting mold having a casting cavity therein a casting face of which is provided

with a longitudinally extending groove, and a pair of liners closing the ends of said cavity, one of said liners having a portion connected thereto and engaged in said groove and extending across the casting cavity and forming a metal-tight joint with the other liner.

15. A slug casting mold comprising opposed members spaced to form casting faces of a mold cavity, the casting face of one of said members having a groove extending longitudinally therein, a pair of liners between said members and closing the ends of said cavity, said liners having ribs connected thereto and engaged in said groove, the rib on one liner terminating short of its cavity closing end, and the rib on the other liner extending across the cavity and beyond the cavity closing end of the other liner.
